MARKING DEVICE

Filed Nov. 8, 1929

Inventor
By *Joseph Oberleitner*
Attorney *Joseph Oberleitner*

UNITED STATES PATENT OFFICE

JOSEPH OBERLEITAN, OF IRVINGTON, NEW JERSEY

MARKING DEVICE

Application filed November 8, 1929. Serial No. 405,632.

This invention relates to improvements in markers, particularly to a marker for clothes or the like, and it is the principal object of my invention to provide a marker of simple construction which can be readily adjusted to any article to be marked and removed therefrom.

It is a well known fact that the markers commonly used in dyeing establishments, by tailors or the like and made of paper, cardboard, or the like, quickly deteriorate, or are torn and become lost greatly to the inconvenience of the people taking in such articles for dyeing, pressing or repairing.

Another object of my invention is the provision of a marker having the point of its pin protected so as to prevent injury to persons.

A further object of my invention is the provision of a marker the pointer pin of which is held in engagement with the article to be marked by the expansion of a spring wound about said pin, and allowing a removal of the marker upon manual contraction of the spring.

A still further object of my invention is the provision of a marker in form of a substantially cylindrical casing bearing conventional marks on its outer surface.

These and other objects and advantages of my invention will become more fully known as the description thereof proceeds and will then be specifically defined in the appended claims.

In the accompanying drawing forming a material part of this disclosure:

Fig. 1 is a side elevation of a marker constructed according to my invention in place on an article to be marked.

Fig. 2 is a side elevation of the marker on an enlarged scale.

Fig. 3 is a longitudinal section through the same.

Fig. 4 is an end view thereof.

Fig. 5 is a cross-section on line 5—5 of Figure 2.

As illustrated, the marker consists of a housing 10, preferably cylindrical in shape and made of metal or any other suitable material marked with identification marks, as

for instance the numeral "300" on its outer surface. Within the cylindrical housing 10, a longitudinally extending bar 11 is provided having its front end formed into a sharp point 12, while its central part is square in cross-section, as at 13, and adapted to snugly fit into a square socket 14 formed in the rear end of the casing, and upon the threaded end 15 of bar 11, a knob 16 is screwed having its outer face corrugated or knurled.

The casing 10 at one side thereof, has its wall cut away, as at 17 to provide a finger hole.

The front end 18 of casing 10 has a comparatively large opening 19 formed therein, the inner wall of which is adapted to be engaged by the point 12 in order to protect the user against injury. A spring 20 is wound about bar 11 between the rear end wall of casing 10 and a collar 21 on bar 11 tending to press the pointed end 12 towards the front.

The device operates as follows:

If it is desired to mark an article of clothing 22, the bar 11 is drawn through the rear end wall of the casing 10 simultaneously tensioning spring 20. If now part of the article to be marked is introduced through the finger hole 17 and the bar 11 is released, the spring 20 will expand and push point 12 through the material of the article, while point 12 of the bar will engage the inner wall of opening 19 and be prevented from injuring the operator.

It will be understood that I have disclosed the preferred form of my device only and that I may make such changes therein as come within the scope of the appended claims without departure from my invention.

Having thus described my invention, what I claim as new and desire to secure by Letters Patent is:

1. A marker for articles comprising a cylindrical casing bearing marks on its outer surface, a pin longitudinally disposed within said casing and having one end pointed, means for protecting said pointed end, and means for allowing a removal of said pin from its protecting means and for project-

ing said pin to engage the material of the article.

2. A marker for articles of clothing comprising a substantially cylindrical casing having one part of its side wall cut away to form a finger hole, an end wall for said casing having a comparatively large opening, a bar longitudinally extending through the casing and having a pointed end adapted to engage the inner wall of said large opening, the opposite end wall of the casing perforated to allow the passage of the opposite end of said bar, a knob on the last mentioned end, a collar on said bar within said casing and a spring wound about said bar between said collar and the end wall of said casing to project upon its expansion the pointed end of said bar into the article to be marked and allowing a withdrawal therefrom upon its manual contraction.
3. A marker for articles of clothing comprising a substantially cylindrical casing having one part of its side wall cut away near one of its ends to present a finger-hole, a front end wall for said casing having a comparatively large opening therein, a pin extending through said casing in the direction of its longitudinal axis, a pointed end on said pin adapted to engage the opening, the body of said pin square in cross section, the opposite end of said casing formed by a square socket to accommodate the body of said pin allowing its passage therethrough, a reduced and threaded outer end on said pin, a knurled knob on said reduced end, a collar on said pin within said casing, and a spring wound about the square part of said pin within said casing resting with one of its ends against said collar and with its other end against said socket.

Signed at New York, in the county of New York, and State of New York, this 17th day of October, A. D. 1929.

JOSEPH OBERLEITAN.
